SANDING OR RUBBING MACHINE

Arthur C. Burleigh, Wellesley, Mass.

Application May 1, 1945, Serial No. 591,336

6 Claims. (Cl. 51—170)

1

This invention relates to manually manipulated sanding machines of the type in which the sanding pad has a gyratory motion, and a counterweight, also having a gyratory motion, is employed to neutralize or balance out the vibration caused by the rapid gyratory motion of the sanding pad.

One of the objects of the invention is to provide a sanding machine of this type which is relatively simple in its construction and comprises relatively few parts.

Another object of the invention is to provide a sanding machine of this type in which the sanding pad assembly and the counterweight are both mounted on and operated from a single drive shaft.

A further object of the invention is to provide a sanding machine of this type in which the single drive shaft is provided with two eccentric portions situated at 180° apart and on which the sanding pad assembly and counterweight are mounted.

A still further object of the invention is to provide a sanding machine of this type having simple and improved means for holding the sanding pad assembly and counterweight from rotation about their axes during their gyratory motion.

Still further objects of the invention are to improve generally sanding machines in the various particulars hereinafter set forth.

In the drawings wherein I have illustrated a selected embodiment of my invention,

Fig. 1 is a vertical sectional view through a sanding machine embodying the invention.

Fig. 2 is a partial sectional view taken at right angles to Fig. 1.

Fig. 3 is a section on the line 3—3, Fig. 1.

Fig. 4 is a section on the line 4—4, Fig. 3.

Fig. 5 is a sectional view similar to Fig. 4 but showing the parts in different position.

Fig. 6 is a section on the line 6—6, Fig. 4.

The machine herein illustrated comprises a head 1 in which is journaled a vertically arranged drive shaft 2, said shaft being mounted in bearings 3 and 4 carried by the head. The drive shaft 2 is herein shown as being driven from a suitable motor 5 which is mounted on the head 1, the motor shaft 6 being connected by a bevel pinion 7 to a bevel gear 8 fast on the drive shaft 2.

The drive shaft 2 is formed with two crank or eccentric portions 9 and 10, said crank portions being 180° apart. The crank portion 10 is provided for by mounting a collar 11 on the lower end of the crank portion 9, which collar has formed integral therewith the crank portion 10.

The sanding pad assembly, presently to be described, is mounted on the crank portion 9 while a counterweight element is mounted on the crank portion 10.

2

The sanding pad assembly comprises the sanding pad element 12 which may be of any suitable or usual construction, a drive plate 13 which is mounted on the crank portion 9 through the medium of ball bearings 14, and means for connecting the sanding pad 12 to the drive plate 13. This means is herein shown as comprising two leg members 15 which are secured to the ends of the drive plate 13 and to the bottom of which is secured a supporting plate 16 to which the sanding pad 12 is detachably secured in any approved way. The bearing 14 for the drive plate 13 is situated centrally of said plate and therefore, the rotation of the drive shaft 2 will operate through the crank portion 9 to give the drive plate 13 and the sanding pad 12 connected thereto a gyratory motion.

17 indicates a counterweight element which is mounted on the crank portion 10 through the medium of ball bearings 18. The crank portion 10 is shown as having a retaining collar 19 secured to its lower end through the medium of a screw 20, said collar 19 serving to retain the ball bearing 18 on the crank portion 10.

The ball bearing 18 for the counterweight is also located centrally thereof, and hence both the counterweight and the sanding pad assembly are centrally mounted on crank portions of the drive shaft, which crank portions are 180° apart.

The rotation of the drive shaft 2 will, therefore produce a gyratory or orbital motion of both the sanding pad assembly and the counterweight 17, said gyratory or orbital motions being in the same orbital direction but 180° out of phase. With this arrangement the tangential movement of either the sanding pad assembly or the counterweight is, at any instant, in a direction opposite to that of the other. Or stated in another way, the movement of the sanding pad assembly in the direction of either the length or the width thereof will always be in a direction opposite to that of the counterweight. As a result the counterweight will neutralize or balance out any vibration caused by the gyratory motion of the sanding pad assembly.

Since the sanding pad assembly, including the drive plate 13, is centrally mounted on the crank portion 9, it is desirable to provide some means for preventing said sanding pad assembly from turning on its axis during its gyratory motion, and the same is true with regard to the counterweight 17.

I have herein provided for this by employing a stationary guide plate 21 which is interposed between the drive plate 13 and the counterweight, said guide plate 21 being secured at its opposite edges by suitable screws 22 to flanges 23 with which the head 1 is provided. The guide plate 21 is provided with a plurality of circular openings 24, in each of which is received the lower end

of a pin 25 depending from the drive plate 13 and also the upper end of a pin 26 rising from the counterweight 17. The pins 25, 26 each have a diameter one-half that of the opening 24, and each opening 24 has a diameter twice the throw of each crank portion 9 or 10. During the gyroscopic motion of the drive plate 13 and the counterweight 17, the pins 25, 26 in each opening 24 will revolve around each other. Said openings and pins thus hold both the drive plate 13 and counterweight 17 from turning about their axes during the gyroscopic motion.

31 indicates a housing member which is secured to the underside of the guide plate 21 and which encloses the counterweight 17.

It will be observed that with my invention, the desired gyroscopic motion of the sanding pad assembly as well as that of the counterweight is secured through the medium of a single crank shaft and with relatively few moving parts.

It will also be observed that the counterweight 17 is located between the drive plate 13 and the sanding pad 12. This places said counterweight in a position relatively near the center of gravity of the sanding pad assembly, which comprises the drive plate 13, the supporting legs 15, the plate 16 and the sanding pad 12. An advantage resulting from having the counterweight located relatively near the center of gravity of the sanding pad assembly is that a better dynamic balance is obtained than if the counterweight were located considerably above or below such center of gravity.

I will preferably make the supporting plate 16 of some suitable insulating material so that the sanding pad 12 will be insulated from the head 1. This will prevent any leakage of current from the motor through the head to the work when the pad 12 is being used for a web rubbing or abrasive operation.

While I have herein referred to the machine as a "sanding machine" and have referred to the pad 12 as a "sanding pad," yet I wish to state that the word "sanding" has been used in a generic sense to indicate any abrasive or rubbing action which would also include a polishing action. The character of the operation performed by the machine, that is, whether it performs an abrasive operation or a rubbing or polishing operation depends upon the character of the active surface of the pad 12. This surface may be such as to produce an abrasive action or it may be a relatively soft surface which will produce a rubbing or polishing action. It will be observed that the character of the surface of the pad 12 does not in any way affect the invention.

My invention, therefore, provides a portable machine for sanding, abrading, rubbing or polishing any surface, which machine is not only simple in construction and comprises relatively few parts but which also is well balanced and operates free from undesirable vibration.

I claim:

1. A machine of the class described comprising a head member, a driving shaft rotatably supported thereby and having two oppositely disposed crank portions, a pad-carrying element mounted on one crank portion, an operating pad secured to said pad-carrying element, said pad providing the entire abrading or rubbing surface of the machine, a counterweight mounted on the other crank portion and means to rotate said driving shaft, both the pad-carrying element and

the counterweight being free to have a bodily gyroscopic motion about the axis of the driving shaft as the latter is rotated with the tangential movement of each always in an opposite direction to that of the other.

2. A machine as in claim 1, provided with means common to both the pad-carrying element and the counterweight to prevent each from turning about its axis during its gyroscopic motion.

10 3. A machine such as described in claim 1, having a stationary guide plate situated between the pad-carrying element and the counterweight and provided with circular apertures, and pins carried by both the pad-carrying element and the counterweight and extending into said apertures.

15 4. A machine of the class described comprising a head member, a driving shaft rotatably supported thereby and having two oppositely disposed crank portions, a pad-carrying element

20 mounted on one crank portion, an operating pad secured to said pad-carrying element, a counterweight mounted on the other crank portion, means to rotate the driving shaft thereby to give both the pad-carrying element and the counter-

25 weight a gyroscopic motion about the axis of the driving shaft, and a stationary guide plate carried by the head member and situated between said crank portions, both the pad-carrying element and the counterweight having means co-operat-

30 ing with said stationary guide plate to prevent them from turning about their axes during their gyroscopic motion.

5. A machine of the class described comprising a head member, a driving shaft rotatably sup-

35 ported thereby and having two oppositely disposed crank portions, a driving plate mounted on one crank portion, leg members depending from said driving plate, a supporting plate secured to the lower ends of the leg members, an op-

40 erating pad carried by said supporting plate, a counterweight carried by the other crank portion and situated between the supporting plate and the driving plate, and means to rotate the driv-

45 ing shaft.

6. A machine of the class described comprising a head member, a driving shaft rotatably sup-

50 ported thereby and having two oppositely disposed crank portions, a driving plate mounted on one crank portion, leg members depending from said driving plate, a supporting plate secured to the lower ends of the leg members, an op-

55 erating pad carried by said supporting plate, a counterweight carried by the other crank portion and situated between the supporting plate and the driving plate, means to rotate the driving

60 shaft thereby to give both the driving plate and the counterweight a gyroscopic motion, a stationary guide-plate situated between the drive plate and the counterweight, and means co-operating with said guide plate to prevent both the drive plate and the counterweight from rotating about their axes during their gyroscopic motion.
